UNITED STATES PATENT OFFICE.

PERCY WALTER DRUITT AND WILLIAM ROBERT GILPIN, OF LONDON, ENGLAND,
ASSIGNORS TO EDWARD HERON ALLEN AND ARTHUR FRANK DE FONBLANQUE,
BOTH OF LONDON, ENGLAND.

JUSTIFYING MECHANISM FOR TYPOGRAPHIC COMPOSING AND CASTING MACHINES.

1,233,995.

Specification of Letters Patent. Patented July 17, 1917.

Application filed December 8, 1915. Serial No. 65,801.

To all whom it may concern:

Be it known that we, PERCY WALTER DRUITT and WILLIAM ROBERT GILPIN, both subjects of the King of Great Britain, both residing in London, England, have jointly invented certain new and useful Improvements in Justifying Mechanism for Typographic Composing and Casting Machines, of which the following is a specification.

10 This invention relates to improvements in justifying mechanism of that class of typographic composing machines in which set values of the matrices, controllers, selectors or type signals composed by the machine are registered on a line registering mechanism, and more particularly in the justifying mechanism associated with the machine described in U. S. application Serial No. 824,534, and in which there is a number of 15 matrix magazines in whose channels are matrices of different set values and wherein provision is made whereby the touching of a key will cause different unit values to be recorded, according as a matrix is released 20 from one or other of the magazines.

25 The object of the present invention is to provide means whereby the unit values registered by the operation of the finger keys may be readily and rapidly changed so that 30 the composing machine can be almost instantly adapted for use in connection with any desired system or plan of distribution of set values.

In the specification above referred to, the 35 changing of the set values recorded by any particular key is accomplished by altering the position of certain adjustable parts of the keyboard actuated mechanism which is described as units accounting levers and 40 which controls the set values recorded. There is a large number of these levers, each of which has to be adjusted individually by hand. The present invention consists solely in providing means for accurately effecting 45 the simultaneous adjustment of these levers.

The invention can be applied to a typographic composing machine having a single magazine or to a machine having a plurality of magazines. It will be described 50 with reference to the accompanying drawings in which Figure 1 is a transverse section, through the keyboard and units accounting mechanism of a composing machine that is supposed to be fitted with two

matrix magazines showing one form of 55 mechanism constructed according to this invention for effecting the simultaneous adjustment of the heights of two series of units accounting levers; and

Fig. 2 is a rear view of the parts shown 60 in Fig. 1, one series of units accounting levers being omitted.

Fig. 3 is drawn to an enlarged scale and is a part plan view and part sectional plan view of a portion of the units accounting 65 mechanism shown in Fig. 1, the section being made by the plane 33 indicated in Fig. 1. It shows alternate levers forming part of one of the two series of the units accounting levers, in register with a series of coöperating 70 bell crank levers.

Fig. 4 shows part plan views similar to and of the same parts as those in Fig. 3 but showing both series of units accounting 75 levers shifted relatively to the bell crank levers, so that the units accounting levers of the second series are in register with the series of bell crank levers. Both in Figs. 3 and 4 certain members shown in Fig. 1 are omitted.

It is not considered necessary to illustrate or describe the magazine or magazines and the releasing mechanism because these form no part of the present invention and may be like those common to typographic machines 85 in which the action of depressing a key, such as *a* in Fig. 1, sets into operation power driven mechanism whereby a key rod, such as *b* in Fig. 1, is lifted to effect the release of a matrix from a magazine. In such a 90 matrix releasing mechanism, the movement of the horizontal key rods *c* is transmitted to the power driven mechanism through the medium of vertical rods *d* (Fig. 1). The movement of the latter is also utilized in the 95 present instance to actuate one or other of a set or series of vertically mounted units accounting levers *e*, *e'* by means of bell cranks *f*.

The invention will be first described with 100 reference to Figs. 1 and 2. As it may be desired to release matrices from either of the two magazines associated with the parts shown in Fig. 1 by touching a finger key, and as the matrices in corresponding channels of the magazines may be of different set values, provision is made whereby the touching of the finger key will cause the set 105

value appropriate to the magazine in use to be recorded. To meet this requirement, there is provided, as is the case in the machine described in the above cited specification, a 5 separate series of units accounting levers for each magazine, each series comprising as many levers as there are key rods. As the parts in Fig. 1 are associated with two magazines two series e, e' of accounting levers 10 are necessary and are shown. The upper and lower ends of each series of units accounting levers are staggered relatively to each other and are so arranged that when one series is in engagement with the bell cranks, 15 the levers of the other series will lie in the spaces between the bell cranks, as indicated in Fig. 3 or in Fig. 4. There is provided means comprising the bar o' and operated by the change-over gear of the magazines and 20 in a manner similar to that described in the above cited specification whereby a guide comb o carried by the bar o' and supporting and positioning the upper ends of the levers may be moved transversely of the key rods 25 to bring one or other of the series of levers into coöperation with the bell cranks according to the magazine which is being used. In Figs. 2 and 3 the levers e' are shown in position to coöperate with the bell 30 cranks f , while in Fig. 4 the levers e are in a coöperative position.

Each units accounting lever e, e' has a rearwardly projecting lug e^2 and has its lower end notched as at e^3 so as to straddle 35 and be supported upon a stepped fulcrum plate g or g' . The steps of a fulcrum plate may be of varying heights so as to be capable of adjusting the positions of the coöperating levers e, e' in such a manner that 40 the rearwardly projecting lug of any one of the units accounting levers may engage with and move rearwardly one or other of a series of primary coupling levers hereinafter referred to, according to the set value it is de- 45 sired to record. A unit accounting lever, when operated on the depression of the corresponding key, will cause a different set value to be recorded according to the particular series of primary coupling levers 50 with which it has been adjusted to coöperate.

The units accounting levers and the coupling levers are divided into groups corresponding in number with the sections of the keyboard which keyboard may conveniently 55 be divided into four sections, as described in the above cited specification. In Fig. 2 portions of four groups of units accounting levers are shown at A, B, C, D, each group containing levers of each set, and there are 60 four groups or sections of primary coupling levers shown at h', h^2, h^3, h^4 . Each group of primary coupling levers extends transversely of all the units accounting levers in its section. Each coupling lever represents 65 a definite set value, and the movement im-

parted to it from the corresponding finger key through the medium of the units accounting levers is transmitted directly or otherwise to a secondary group of coupling levers i and from thence by means of reversing levers k to the releasing latches l of 70 a suitable power relay, whereby the units accounting mechanism is operated to record the appropriate set value. The power relay may be of any suitable kind and may, as 75 shown in Fig. 1, include a continuously rotating shaft u and a ratchet disk v keyed thereto, a cam w loosely mounted on the shaft and carrying a spring-urged pawl x , held out of engagement with the ratchet by 80 a cam plate y controlled by one of the latches l . When the pawl x is released by the cam plate y , the pawl engages the rotating ratchet disk v , whereupon the cam w revolves and actuates a pivoted lever z operatively connected with an appropriate units registering device which is not shown, but may be of known construction, for instance similar to that referred to and illustrated in our U. S. specification Serial No. 90 824,534. In Fig. 2 the lever groups h^2, h^3 coöperate directly with the secondary coupling levers i , while the groups h', h^4 coöperate indirectly through sets of auxiliary coupling levers j', j^2 respectively. 95

In order to allow greater latitude in choosing a set value for any particular magazine channel, the secondary group of coupling levers i may be adapted in some cases to receive motion from two primary 100 coupling levers in adjacent groups both representing the same set value, so that some overlapping of the groups occurs, for instance the last two or three levers of a group j , may be coupled with the same levers of the secondary group i as are the first two or three levers of an adjacent group of primary coupling levers. 105

To enable the unit accounting levers to be readily and simultaneously adjusted to any 110 of their several positions, the fulcrum plates g, g' , upon which they are supported are attached respectively to a detachable bar or bars m, m' extending transversely of the keyboard. This bar or bars held in position 115 against the top of the recesses p formed for their reception in the sides of the frame q or against suitable stops, not shown, by a lever r controlled through spring s by handle t , can be lowered by releasing the latch that would be provided to lock the lever, thus 120 allowing the units accounting levers to fall to a common level, in which supporting lugs e^4 , projecting from the sides of the accounting levers, will rest upon a guide comb n 125 located near the lower end of the latter levers. The fulcrum plate bar can now be drawn transversely from beneath the units accounting levers, and another bar substituted bearing a fulcrum plate which has a 130

series of steps that serve to adjust the levers *e, e'* by heights according to the set value of the font of matrices or other elements to be brought into use with the desired scheme of allocation of set values. The raising of this bar by means of lever *r* into the working position will bring the units accounting levers into position to register the correct set values.

10 As before stated, the lower ends of the various series of units accounting levers corresponding to different magazines are in different planes, thus permitting the employment of an independent fulcrum plate 15 bar for each magazine, and allowing such bars *g g'* to be changed, one independently of the other. In a machine that has merely a single magazine, there would be only one set of unit accounting levers, and one fulcrum plate.

Having thus described the said invention and the best means we know of carrying the same into practical effect, we claim:—

1. In a typographic composing machine 25 of the character referred to, which is controlled by the keys of a keyboard and includes a magazine containing a set of elements capable of being composed by the machine, a justifying mechanism comprising a device for registering the set unit value of each element composed in line, mechanism operated by the finger keys for actuating said device to record the set value of the element represented by the finger key 30 struck, said mechanism comprising a set of adjustably mounted units-accounting levers actuatable by the finger keys, and means for adjusting the units-accounting levers simultaneously to change the set value registered by the said registering device on the 35 operation of a key, substantially as described.

2. In a typographic composing machine, 45 of the character referred to, which is controlled by the keys of a keyboard and includes a magazine containing a set of elements capable of being composed by the machine, a justifying mechanism comprising a device for registering the set unit value 50 of each element composed in line, mechanism operated by the finger keys for actuating said device to record the set value of the element represented by the finger key struck, said mechanism comprising a set of 55 adjustably mounted units-accounting levers actuatable by the finger keys, primary coupling levers operated by the units-accounting levers, secondary coupling levers operated 60 by the primary coupling levers and a power driven mechanism operatively coupled with the set value registering device and controlled by the secondary levers, and means for adjusting the units-accounting levers simultaneously to change the set value 65 registered by the said registering device on

the operation of a key, substantially as described.

3. In a typographic composing machine of the character referred to, which is controlled by the keys of a keyboard and includes a magazine containing a set of elements capable of being composed by the machine, a justifying mechanism comprising a device for registering the set unit value of each element composed in line, 70 mechanism operated by the finger keys for actuating said device to record the set value of the element represented by the finger key struck, said mechanism comprising a set of adjustably mounted units-accounting levers actuatable by the finger keys, and means for adjusting the units-accounting levers simultaneously to change the set value registered by the said registering device on the 75 operation of a key said means comprising an interchangeable stepped fulcrum plate, the steps of the plate being adapted to serve as pivots for and to adjust the heights of the units-accounting levers, substantially as described.

4. In a typographic composing machine of the character referred to, which is controlled by the keys of a keyboard and includes a magazine containing a set of elements capable of being composed by the machine, a justifying mechanism comprising a device for registering the set unit value of each element composed in line, mechanism operated by the finger keys for actuating said device to record the set value of the element represented by the finger key struck, said mechanism comprising a set of adjustably mounted units-accounting levers actuatable by the finger keys, and means for adjusting the units-accounting levers simultaneously to change the set value registered by the said registering device on the 90 operation of a key, the said means comprising an 95 adjustably mounted interchangeable stepped fulcrum plate, the steps of the plate being adapted to serve as pivots for and to adjust the heights of the units-accounting levers, and means for moving the fulcrum plate into and out of engagement with the said 100 levers for the purpose described.

5. In a typographic composing machine of the character referred to, which is controlled by the keys of a keyboard and includes a number of magazines each containing a set of elements capable of being composed by the machine, a justifying mechanism comprising a device for registering the set unit value of each element composed in line, mechanism operated by the finger keys for actuating said device to record the set value of the element represented by the finger key struck, said mechanism comprising a corresponding number of sets of adjustably mounted units-accounting levers arranged in groups and actuatable by 110 115 120 125 130

the finger keys, and means for adjusting all the units-accounting levers simultaneously to change the set value registered by the said registering device on the operation of 5 a key, substantially as described.

6. In a typographic composing machine of the character referred to, which is controlled by the keys of a keyboard and includes a number of magazines each containing 10 a set of elements capable of being composed by the machine, a justifying mechanism comprising a device for registering the set unit value of each element composed in line, mechanism operated by the finger keys 15 for actuating said device to record the set value of the elements represented by the finger key struck, said mechanism comprising a corresponding number of sets of adjustably mounted units-accounting levers arranged 20 in groups and actuatable by the finger keys, primary coupling levers operated by the units-accounting levers, secondary coupling levers operated by the primary coupling levers and a power driven 25 mechanism operatively coupled with the set value registering device and controlled by the secondary levers and means for adjusting all the units-accounting levers simultaneously 30 to change the set value registered by the said registering device on the operation of a key, substantially as described.

7. In a typographic composing machine of the character referred to, which is controlled by the keys of a keyboard and includes 35 a number of magazines each containing a set of elements capable of being composed by the machine, a justifying mechanism comprising a device for registering the set unit value of each element composed in line, mechanism operated by the finger keys 40 for actuating said device to record the set value of the element represented by the finger key struck, said mechanism comprising a corresponding number of sets of adjustably mounted units-accounting levers arranged 45 in groups and actuatable by the finger keys, and means for adjusting all the units-accounting levers simultaneously to change the set value registered by the said 50 registering device on the operation of a key, said means comprising interchangeable stepped fulcrum plates, the steps of the plates being adapted to serve as pivots for and to adjust the heights of the units- 55 accounting levers, substantially as described.

8. In a typographic composing machine of the character referred to, which is con-

trolled by the keys of a keyboard and includes a number of magazines each containing a set of elements capable of being composed by the machine, a justifying mechanism comprising a device for registering the set unit value of each element composed in line, mechanism operated by the finger keys 60 for actuating said device to record the set value of the element represented by the finger key struck, said mechanism comprising a corresponding number of sets of adjustably mounted units-accounting levers actuatable by the finger keys, and means for 65 adjusting the units-accounting levers of any one set simultaneously to change the set value registered by the said registering device on the operation of a key, the said means comprising interchangeably and independently mounted stepped fulcrum plates the steps of the plates being adapted to serve as pivots for and to adjust the heights of the units-accounting levers of the respective sets, 70 substantially as described.

9. In a typographic composing machine of the character referred to, which is controlled by the keys of a keyboard and includes a number of magazines each containing a set of elements capable of being composed by the machine, a justifying mechanism comprising a device for registering the set unit value of each element composed in line, mechanism operated by the finger keys 85 for actuating said device to record the set value of the element represented by the finger key struck, said mechanism comprising a corresponding number of adjustably mounted units-accounting levers actuatable by the finger keys, and means for adjusting 90 the units-accounting levers simultaneously to change the set value registered by the said registering device on the operation of a key, the said means comprising adjustably mounted interchangeable stepped fulcrum plates, the steps of the plates being adapted to serve as pivots for and to adjust the heights of the units-accounting levers, and means for moving the fulcrum plates into 95 and out of engagement with the said levers 100 for the purpose described.

In testimony whereof we have signed our names to this specification in the presence of two subscribing witnesses.
